TO BALT MANUFACTURING COMPANY, OF ATLANTA, GEORGIA, A CORPORATION OF
GEORGIA.

ARC GAP.

Application filed May 25, 1920. Serial No. 384,921.

To all whom it may concern:

Be it known that I, CHARLES E. BENNETT, a citizen of the United States of America, residing at Atlanta, in the county of Fulton 5 and State of Georgia, have invented certain new and useful Improvements in Arc Gaps, of which the following is a specification.

My invention relates to arc gaps, and my object is to provide a gap installation having 10 a spark-over rating which is maintained substantially constant regardless of varying moisture conditions at the gap. While this may be accomplished in different ways, I have indicated, as an embodiment of my 15 ideas, a terminal construction of such character that the drop in the gap rating normally incident to the presence of moisture at the gap (as in a rain storm) is automatically compensated by the altered electrical conditions at the terminals. 20

In the accompanying drawings—

Fig. 1 is a broken side elevation of an arc gap illustrative of my invention;

Figs. 2 and 3 are more or less diagrammatic views illustrating the lines of force 25 between the gap terminals under dry and wet conditions, respectively;

Figs. 4 and 5 are more or less diagrammatic side elevations of modified constructions of the terminals; and 30

Fig. 6 is an explanatory diagram.

While the present invention is susceptible of adaptation to various installations in which an arc gap may be used, I have shown 35 it in a form applicable to surge or lightning arresters of the type illustrated in my co-pending application Serial No. 306,383, filed June 24, 1919, designed to protect the equipment of an alternating current power line.

In an installation of this type, the ground connection through the arrester requires an arc gap, the terminals of which are spaced a predetermined distance apart, depending upon the normal voltage of the protected 40 line.

The spacing of the terminals must be such that while no arc-over will occur under ordinary line conditions, such as harmless surges, yet when dangerous current is imposed upon the line, it will at once jump the gap and discharge to ground without injury to the equipment installed in the line. 45

The spacing for a given arc-over voltage differs with the character of the arc terminals; thus, for needle point terminals the

spacing must be considerably greater than 55 for sphere terminals; while for sphere terminals, those of greater size may be set closer together than those of smaller size, for a given gap rating. The relative setting for terminals of these types is illustrated in Fig. 6. As will be observed, the distance *a* between the needle terminals 7 is considerably greater than the distance *b* between the sphere terminals 8; while the distance *c* between the large spheres 9 is 60 still shorter.

One of the greatest external factors which affect the gap rating is moisture in the form of fog, mist or rain. The effect of rain on a sphere gap lowers the rating from 40 to 50%. 70 Its effect on a needle gap is much less, by reason of the greater normal spacing between the points and the fact that the latter gather little moisture upon their surfaces. But while a needle gap possesses this desirable 75 characteristic, on the other hand it is objectionable for the reason that there is certain lag (incident to corona formation) in the striking of the arc across the gap. In an installation which requires as close an 80 approximation to instantaneous action as can be attained, such a delay is objectionable.

On the other hand, an arc forms instantly between sphere terminals, and the use of the latter is therefore preferred. But a 85 sphere gap has the draw-back above noted, that rain greatly decreases the gap rating, and excessive spacing between the spheres is necessary to prevent grounding the line through the gap at normal voltage under 90 wet weather conditions. This spacing renders the gap less sensitive than desired to take care of line surges which may occur under dry weather conditions. In other words, the gap between the fixed spheres 95 must be adjusted for wet weather conditions, and is thus not sufficiently sensitive under dry weather conditions.

I have now discovered that this difficulty may be overcome by associating with the 100 gap terminals a body of some material which is inactive under dry weather conditions, but becomes effective under wet weather conditions to counteract the decreased rating of the gap. The gap terminals may therefore be sensitively set to 105 take care of surges under dry weather conditions, and still be free from danger of

arc-over at line voltage under wet weather conditions.

- Just what form, shape or substance is used for the associated terminal element is not essential so long as the desired effect is secured. In Fig. 1, however, I have shown the metallic spheres 8 substantially embedded in a body of insulating material 10, but exposed on their adjacent faces.
- 10 The exposed metallic terminals are respectively connected by conductors 11 to metallic caps 12 and 13 mounted on the post insulators 14. The cap 12 is connected by lead 15 to the protected power line 16, while cap 13 is connected by lead 17 to ground through an arrester (not shown). The spacing between the metal terminals 8 is adjusted to that required to discharge a dangerous line surge by arc-over under dry weather conditions. The lines of force or electrostatic flux between the metallic spheres are diagrammatically illustrated at 18 in Fig. 2. Should a rain storm occur, however, which would normally so lower the gap rating that an arc-over at line voltage would normally follow, the water falling upon the insulating spheres 10 coats the latter with a conducting film and transforms their surfaces into conductors. The electrical conditions at the terminals are thereby automatically so altered, that an arc-over does not take place. Observations have indicated a dispersion of the lines of force or electrostatic flux somewhat as indicated diagrammatically at 19, Fig. 3.

The particular nature of the material 10 is subject to considerable variation. I have found that while porcelain of the general type used in insulators, may under proper conditions serve the purpose satisfactorily, still better results are obtained when a more or less porous insulating material, such as lava, cement, or special clay compounds, is used, which not only affords a conducting surface-film of moisture, but is also permeated by the moisture so as to actually afford a conductor body when wet. The approximation to a metal terminal of large size is thus more close.

50 As above stated, the particular form of terminal, and of the associated normally insulating body, is subject to considerable variation. Thus, in Fig. 4 I have shown the sphere terminal in the form of a plate 20, and the associated insulating material in the form of a larger disc 21.

In Fig. 5 I have shown an insulator disc 21 of this type associated with a horn gap terminal 22 instead of the plate 20 of Fig. 60 4. Various other constructions will readily occur to those dealing with the problem.

The underlying thought of the specific application of my invention is to provide a metallic gap terminal having associated therewith a non-conductor serving, when

wet, to increase the electro-conductive area of the gap terminal. The electrostatic flux field between the gap terminals thus automatically expands and contracts, depending upon moisture conditions at the terminals, and thus automatically maintains the gap rating substantially constant, although the resistance of the gap varies. The particular nature of the associated element of the gap terminal is subject to variation, but I prefer a substance which, while an insulator when dry, is more or less readily permeated by moisture when wet.

75 Various adaptations and modifications of the invention will readily occur to those dealing with the problem, without departing from what I claim as my invention.

I claim—

1. In the arc gap installation, a pair of electrodes operative when dry, and associated means operative only when wet to compensate the lowered impedance of the gap in the presence of moisture and serving to maintain the gap rating substantially uniform under wet and dry conditions.

80 2. In an arc gap installation, a pair of electrodes operative when dry, and associated means operative when wet to vary the electrostatic flux field at the gap, and to maintain the gap rating substantially constant.

85 3. In an arc-gap installation, a pair of spaced electrodes having, when dry, a relatively restricted zone of electrostatic flux therebetween, and associated means serving, when wet, to enlarge said zone under moisture conditions at the gap.

90 4. In an arc-gap installation, metallic terminals and associated insulating bodies serving when wet to enlarge the conducting area of the terminals.

95 5. In an arc-gap installation, a metallic terminal and an associated insulator electrically connected thereto under moisture conditions and serving to enlarge the conducting area of said terminal and thus to expand the electrostatic flux field at the gap.

100 6. In an arc-gap installation, a metallic terminal and an associated moisture permeable insulator electrically connected thereto and serving under moisture conditions to effectively enlarge the conductive area of said terminal.

105 7. In an arc-gap installation, a pair of electrodes, and means associated therewith and responsive to moisture conditions at the gap for varying the electrostatic flux field between the electrodes.

110 8. In an arc-gap installation, a pair of electrodes shrouded in moisture receiving insulator means associated with said terminals to vary the flux field between the same under wet and dry conditions at the gap.

115 9. In an arc-gap installation, a pair of

- spaced electrodes, and insulator means associated therewith and operative under moisture conditions at the gap to substantially prevent corona formation between the electrodes.
10. In an arc-gap installation, a metallic electrode and an associated moisture permeable insulator having a curvilinear surface facing the gap.
- 10 11. In an arc gap installation, a metallic electrode and an associated electrode surface electrically connected thereto when wet and of a character serving to prevent globule formation thereon under moisture conditions at the gap.
- 15 12. In an arc gap installation, a metallic electrode and an associated electrode sur-
- face of non-conducting material electrically connected in multiple to said metallic electrode by moisture.
- 20 13. The method of stabilizing an arc gap rating under wet and dry conditions at the gap, which comprises automatically varying the flux field between the gap terminals by moisture applied to the terminals.
- 25 14. The method of stabilizing an arc gap rating under wet and dry conditions at the gap, which comprises automatically enlarging the conducting area of the terminals by the application of moisture thereto.
- 30 In testimony whereof I have signed my name to this specification.

CHARLES E. BENNETT.
